GRINDING WHEEL TRUING APPARATUS

Lennart A. Kasparsen, Worcester, Mass., assignor
to Norton Company, Worcester, Mass., a corporation of Massachusetts

Application July 11, 1941, Serial No. 401,963

2 Claims. (Cl. 125—11)

The invention relates to grinding machines, and more particularly to a grinding wheel truing apparatus for generating either a true cylindrical or a curved face on the operative surface of a grinding wheel.

One object of the invention is to provide a simple and thoroughly practical combined radial and straight grinding wheel truing apparatus. Another object of the invention is to provide an improved radial grinding wheel truing apparatus which is arranged to true either a cylindrical face, an arcuate face, or a combined cylindrical and arcuate face on the operative surface of a grinding wheel. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiment of the mechanical features of this invention,

Fig. 1 is a fragmentary cross-sectional view through the grinding machine, illustrating the improved grinding wheel truing apparatus in elevation and showing the grinding wheel feeding mechanism partly in section;

Fig. 2 is a vertical sectional view, on an enlarged scale, through the grinding wheel truing apparatus;

Fig. 3 is a plan view, on an enlarged scale, of the grinding wheel truing apparatus; and

Fig. 4 is a fragmentary sectional view, on an enlarged scale, taken approximately on the line 4—4 of Fig. 3, showing the detachable actuating lever for the truing apparatus.

A grinding machine has been illustrated in the drawings comprising a base 10 having a transversely movable grinding wheel slide 11 mounted on the usual V-way and flat way (not shown) on the base. The wheel slide 11 serves as a support for a rotatable grinding wheel spindle 12 which in turn supports a rotatable grinding wheel 13. The grinding wheel spindle 12 may be driven by any suitable source of power, such as those well known in the art, that is, either an electric motor mounted on the wheel slide 11, or an overhead drive shaft. A driving belt 14 transmits power from the source (not illustrated) to a pulley 15 mounted on the end of the wheel spindle 12.

The grinding wheel slide 11 may be moved transversely relative to the base 10 by a suitable

wheel feeding mechanism such as, for example, that shown in the prior U. S. patent to Charles H. Norton, No. 762,838 dated June 14, 1904, to which reference may be had for details of disclosure not contained herein. This feeding mechanism may comprise a depending half nut 16 which is fixedly mounted on the under side of the wheel slide 11 and a rotatable feed screw 17 which is rotatably journaled in bearings (not shown) in the base 10. The forward end of the feed screw 17 is slidably keyed within a rotatable sleeve 18 which is journaled in a bearing 19 formed within the base 10. A shaft 20 is formed integral with the sleeve 18 and is journaled in a bearing 21 formed in the base 10. A gear 22 is mounted on the outer end of the shaft 20 and meshes with a pinion 23. The pinion 23 is rotatably supported on a stud (not shown) to rotate with a gear 24 which is formed as part of a manually operable feeding wheel 25. A micrometer wheel feed adjusting mechanism 26 is provided whereby the infeeding movement of the grinding wheel 23 may be stopped in a desired adjusted position.

25 A longitudinally reciprocable work supporting table 27 is slidably supported on a flat way 28 and a V-way 29 formed on the upper surface of the base 10 to support the table for a longitudinal reciprocatory movement relative to the base 10. The table 27 serves as a support for a swivel table 30 which in turn serves as a support for a rotatable work piece (not shown) and also as a support for a truing apparatus, as illustrated in the drawings. The table 27 is arranged to be traversed longitudinally by means of a rack bar 31 depending from the under side of the table 27 by means of a manually operable traverse mechanism such as, for example, substantially the same as that shown in the prior patent to Norton above referred to.

30 The improved grinding wheel truing apparatus may comprise a base 32 which is provided with bearing surfaces 33, 34 and 35 (Fig. 2) which mate with correspondingly shaped surfaces formed on the upper portion of the swivel table 30. A clamping member 36 is pivotally supported by a stud 37 on the base member 32. The clamping member 36 is connected by means of a link 38 with a rod 39 which is slidably mounted within an aperture 40 formed in the base member 32. The left-hand end of the rod 39 is provided with a threaded portion 41 which is engageable with a manually operable nut 42 by means of which the clamping member 36 may be actuated either to clamp the steadyrest base

member 32 in an operative truing position on the swivel table 30, or may be unclamped to facilitate removal of the truing apparatus from the swivel table after a truing operation has been completed.

An arcuate shaped member 45 is fixedly supported on the steadyrest base 32 by means of a plurality of screws 46 and 47. The arcuate shaped member 45 is provided with an inverted V-shaped slideway 48 which serves as a support for a truing tool slide 49. The truing tool slide 49 is provided with a correspondingly shaped inverted V-way which mates with the V-way 48. A plate 50 is fastened to the under side of the truing tool slide 49 (Figs. 2 and 4) and is provided with a bearing surface 51 which engages and mates with the under surface of the arcuate plate 45. A shim 52 is interposed between the plate 50 and the truing tool slide 49 by means of which the parts may be adjusted so that the slide 49 is slidably held without lost motion on the inverted V-way 48.

The truing tool slide 49 is provided with a cylindrically shaped aperture 53 which serves as a support for a truing tool holder 54 which supports a diamond or truing tool 55. The holder 54 is held against a rotary movement by means of a key 56 and is arranged to be clamped in adjusted position by means of a binder screw 57. A stop screw 58 is screw threaded into an end cap 59 and is arranged to butt against the end of the holder 54. The screw 58 serves to facilitate adjustment of the position of the diamond or truing tool 55 relative to the axis of movement of the arcuate slideway 48 so that the radius of curvature generated or trued upon the periphery of the grinding wheel 13 may be readily adjusted as desired. A pair of adjustable stop screws 60 and 61 are fixedly supported relative to the steadyrest base 32 and serve in a manner to be hereinafter described to limit the arcuate swinging movement of the truing tool slide 49.

A locating plunger 65 is slidably supported by an upwardly extending portion 66 of the steadyrest base 32. The tapered end portion of the plunger 65 is arranged to be moved into a mating notch 67 formed in the truing tool slide 49 and serves to locate and hold the diamond 55 in a center position for truing a cylindrical face on the grinding wheel 13. The upper part of the boss 66 is provided with a slot 68. A binder or clamping screw 69 passes through a clearance aperture on one side of the slot 68 and is screw threaded into the boss on the other side and serves to clamp the plunger 65 in adjusted position when desired.

In order to facilitate an arcuate swinging movement of the truing tool slide 49, a manually operable, readily detachable handle 70 is provided which is shaped on its forward end portion to engage a socket 71 fixedly supported on the upper surface of the truing tool slide 49. The handle 70 is provided with a downwardly extending integral stop lug 72 which is arranged to move in the path of the stop screws 60 and 61 so as to thus limit the arcuate swinging movement of the truing slide 49. When it is desired to true a radius or curved face on the corner of the grinding wheel 13, the handle 70 is inserted in the socket 71 and the plunger 65 is moved toward the left (Figs. 2 and 3) to disengage the plunger 65 from the notch 67. The manually operable lever 70 is then manually swung through an arc of substantially ninety degrees into position 70a (Fig. 3), during which swinging movement the truing

tool 55 swings from the full line position (Fig. 3) into the broken line position 55a so that it generates a quadrant upon the face of the grinding wheel. It will be readily apparent from the foregoing disclosure that by adjusting the position of the diamond or truing tool 55 toward or from the axis of the arcuate swinging movement of the truing tool slide 49, the radius of curvature generated on the wheel periphery may be varied as desired.

In case it is desired to true a radius or curved face on the other corner of the grinding wheel 13, a second socket 73 is provided on the truing tool slide. The manually operable handle 70 may be inserted within the socket 73 and the truing tool slide 49 swung in a counterclockwise direction until the stop lug 72 engages the stop screw 61 to generate a radius or curved face on the other corner of the grinding wheel. By merely shifting the manually operable handle from socket 71 to socket 73 or vice versa, the truing apparatus is adapted for truing a radius on either corner of the wheel or may true a cylindrical face thereon by locking the truing tool slide 49 in a center position.

The operation of this truing apparatus will be readily apparent from the foregoing disclosure. Assuming the stop screws 60 and 61 to have been previously adjusted to facilitate a swinging of the truing tool 55 through an angle of substantially ninety degrees, and assuming the truing tool 55 to have been radially adjusted to generate the desired radius on the grinding wheel 13, the grinding wheel 13 is fed into a forward or grinding position, after which the micrometer adjusting mechanism 26 is adjusted to allow an advancing movement of the grinding wheel by an amount it is desired to true from the face thereof.

In case it is desired to true a cylindrical face on the wheel, the plunger 65 is maintained in engagement with the notch 67, in which position the table 21 may be traversed longitudinally to traverse the truing tool 55 across the peripheral face of the grinding wheel 15 to generate a cylindrical surface thereon. If it is desired to true a radius or curved face thereon, the manually operable handle 70 is inserted in either the socket 71 or the socket 73, the plunger 65 is then withdrawn from the notch 67, and the manually operable handle or lever 70 is swung in either a clockwise or counterclockwise direction through an arcuate path of substantially ninety degrees to generate a radius on the desired corner face of the grinding wheel.

It will be readily apparent that, as illustrated in Fig. 3 of the drawings, if desired a combined cylindrical surface and radius may be generated on the operative face of the grinding wheel, that is, by first locking the diamond in a position as shown in Fig. 3 to generate a cylindrical face, after which the plunger 65 is released from the notch 67 and the truing tool slide swung in an arcuate path in a clockwise direction to generate the curved face or radius thereon.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine truing apparatus having a base which is arranged to be detachably mounted on a grinding machine table, an arcuate V-shaped slideway fixedly supported on said base, a truing tool slide having a slideway to mate with said V-shaped slideway, a truing tool adjustably supported on said slide, a pair of adjustable stop screws supported on said base, a manually operable handle which is detachably supported, a pair of spaced sockets on said slide to facilitate locating said handle in one of two positions on said slide to swing said slide and truing tool through an arcuate path to true a radius on either corner of a peripheral face of a grinding wheel, said handle having a depending portion which moves in the path of said stop screws to limit the arcuate swinging movement of the truing tool.

2. In a grinding machine truing apparatus having a base which is arranged to be detachably mounted on a grinding machine table, an arcuate V-shaped slideway fixedly supported on said base, 5 a truing tool slide having a way mating with the arcuate V-shaped slideway, a truing tool adjustably supported on said slide, a pair of adjustable stops, means including a manually operable locating pin to locate said slide and truing tool in position for truing a cylindrical face on a grinding wheel, a readily detachable, manually operable handle on said slide, a pair of spaced sockets on said slide to facilitate attaching said handle in one of two positions, and a lug formed integral 10 with said handle which is arranged in the path of said stops to limit the arcuate movement of said slide.

LENNART A. KASPARSON.
